(57) CLAIM

The ornamental design for a dispenser holder, as shown and described.

DESCRIPTION

FIG. 1 is a top, right, front perspective view of a dispenser holder showing my new design;

FIG. 2 is a top, right, rear perspective view thereof;

FIG. 3 is a front elevational view thereof;

FIG. 4 is a right elevational view thereof, the left elevational view being a mirror image thereof;

FIG. 5 is a rear elevational view thereof;

FIG. 6 is a top plan view thereof; and,

FIG. 7 is a bottom plan view thereof.

The broken-line disclosure in the views is understood to represent portions of the article in which the claimed design is embodied, but which form no part of the claimed design.

1 Claim, 3 Drawing Sheets
